UNITED STATES PATENT OFFICE.

WILLIAM M. PFITZNER, OF BROOKLYN, NEW YORK.

DESIGN FOR A FLOWER-STAND.

SPECIFICATION forming part of Design No. 17,205, dated March 22, 1887.

Application filed February 9, 1887. Serial No. 227,077. Term of patent 3½ years.

To all whom it may concern:

Be it known that I, WILLIAM M. PFITZNER, a citizen of the United States, residing at Brooklyn, county of Kings, State of New York, have 5 invented a new and original Design for a Flower-Stand, of which the following is a specification, reference being had to the accompanying engraving, forming part thereof, and representing a perspective view of my 10 newly-designed flower-stand.

The leading feature of my design consists of a receptacle having an indented surface and mounted upon an upright surrounded by ornaments and supported on curved legs.

15 *a* is a tapering receptacle having an indented surface, and provided with an upper flange, *b*, and lower flange, *c*. The recepta-

cle *a* is mounted upon an upright, *d*, having a twisted or spiral outline, and surrounded by ornaments *e*, that are made of double-conical 20 shape—that is to say, they taper from the center both toward the top and the bottom. *f* is a base-plate connected with ogee legs *g*, having feet *h*.

What I claim is—

25 The design for a flower-stand, consisting of receptacle *a*, having indented surface and flanges *b* *c*, and of the spiral upright *d*, double-conical ornaments *e*, base-plate *f*, and curved legs *g*, substantially as shown.

WILLIAM M. PFITZNER.
